RALPH E. JONES, OF THE UNITED STATES ARMY, FORT GEORGE G. MEADE, MARYLAND

PROJECTILE

Application filed November 6, 1931. Serial No. 573,454.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 This invention relates to a projectile and more particularly it has reference to an armor-piercing bullet.

In establishing a defense against armored vehicles it is necessary to provide projectiles 0 that will penetrate the armor, and preferably such projectile, after penetration, should be capable of affording a large danger zone and be sufficiently destructive to incapacitate the vehicle and its crew. A suitable projectile of this character is an explosive shell but inasmuch as it requires a fuse it must be of a relatively large caliber, and must be discharged from a correspondingly large weapon.

20 The principal object of the present invention is to provide a small caliber, non-explosive bullet that will separate into a large number of pieces when it has penetrated armor plate. The bullet may be discharged 25 from a small light weapon that may be easily transported and readily employed.

With the foregoing and other objects in view, the invention resides in the novel arrangement and combination of parts and in 30 the details of construction hereinafter described and claimed, it being understood that changes in the precise embodiment of the invention herein disclosed may be made within the scope of what is claimed without departing 35 from the spirit of the invention.

A practical embodiment of the invention is illustrated in the accompanying drawing, wherein:

Fig. 1 is a longitudinal sectional view of 40 the improved projectile, taken on the line 1-1 of Fig. 3.

Fig. 2 is a view in side elevation of the component parts of the projectile casing prior to assembly.

45 Fig. 3 is a detail sectional view on the line 3-3 of Fig. 1.

Referring to the drawing by character of reference:

The projectile comprises a solid armor- 50 piercing head A and a hollow body B whose

rear end is closed by the base 5. The head and the body are formed with a plurality of annularly spaced fingers or prongs, preferably three on each member, designated respectively a and b. The fingers are disposed 55 parallel to the axis of the members and also disposed towards one another, that is one set rearwardly and one set forwardly, so that they may be interfitted upon relative axial movement. When thus assembled the head and body cooperate to provide a completely 60 closed container. As shown in Fig. 3 the fingers a have a slightly greater radial thickness and a slightly less circumferential width than the fingers b, for a purpose that will appear hereinafter.

Within the projectile there is placed a core consisting of a plurality of equal segments, preferably twelve, and of such length that they will fit between the base 5 and the head 70 A. By virtue of the differences in width of fingers a and b the segments 6-6 in pairs will extend circumferentially beyond the inner edges of each finger a, and the segments 7-7 alternately placed in pairs, will correspondingly be of less peripheral width than 75 the inside of the fingers b. Also by virtue of the difference in thickness of the fingers a and b the radius of the segments 7 will exceed the radius of the segments 6.

In assembling the projectile the segments 7 have a moderately close fit against the inside 80 of the body B and fingers b that is sufficient to insure the assembly of the projectile under ordinary circumstances, yet not so close as to 85 require a great amount of force to withdraw them from the body. On the other hand the segments 6 have an extremely close fit with respect to the fingers a of the head A.

The forward portion of the external wall 90 of the body B is gradually reduced in diameter as at 8 to provide a shoulder 9. A rotating band 10 is placed in an annular groove 11 in rear of the shoulder 9 and projects beyond the wall of the body B for the usual purpose 95 of taking the rifling of a gun and thereby imparting rotation to the projectile. The rear portion of the head A, designated at 12, constitutes a bourrelet for centering and guiding and it is to be understood that where the 100

metal of the head is unsuited to contact the rifling a band of appropriate metal may be applied at this point in any approved manner.

- 5 When the projectile is fired from a gun rotation is imparted to the hollow body B by the rotating band and the head A also rotates therewith by virtue of the interengagement of the fingers *a* and *b* and the segments 6 and 7.
- 10 While the segments and particularly the segments 6 are fitted tightly enough to overcome the forces of inertia during rotation they would still rotate despite any looseness because the segments 7 overlap the fingers *a*.
- 15 When the projectile penetrates armor, the friction of the armor against the body B and the engagement of the armor with the shoulder 9 and rotating band 10 will cause the body B to be stripped from the head A which continues on its flight at a reduced velocity. The rotation of the head A and its tightly held segments 6 will rotate the segments 7 and carry them along until they are free of the body, whence they will be thrown clear due to the action of centrifugal force. When the head A strikes some substantial element in the interior of the tank or the opposite wall the shock of impact will cause the segments 6 to separate from the head. The twelve segments thus released will correspond to fragmentation of an explosive shell.

I claim.

1. A projectile comprising a head having spaced rearwardly extending fingers, a hollow body having spaced forwardly extending fingers adapted to fit between the fingers of the head, the fingers on the body being of greater width and less thickness than the fingers on the head, a plurality of segments of equal width within the body and the interfitted fingers, alternate pairs of segments having a moderately close contact with the body and an extremely close contact with the fingers of the head.
- 45 2. A projectile comprising a head having spaced rearwardly extending fingers, a hollow body having spaced forwardly extending fingers adapted to fit between the fingers of the head, the fingers on the body being of greater width and less thickness than the fingers on the head, a plurality of segments of equal width within the body and the interfitted fingers, some of the segments closely contacting the fingers of the head and the remaining segments less closely contacting the body.
- 55 3. A projectile comprising a head having spaced rearwardly extending fingers, a hollow body having spaced forwardly extending fingers adapted to fit between the fingers of the head, the fingers on the body being of greater width and less thickness than the fingers on the head, a plurality of segments of equal width within the body and the in-

terfitted fingers and contacting the walls thereof.

4. A projectile comprising a head having spaced rearwardly extending fingers, a hollow body having spaced forwardly extending fingers adapted to fit between the fingers of the head, the fingers on the body being of greater width and less thickness than the fingers on the head, and a plurality of segments within the body and interfitted fingers.

5. A projectile comprising a head having spaced rearwardly extending fingers, a hollow body having spaced forwardly extending fingers adapted to fit between the fingers of the head, and a plurality of segments within the body and interfitted fingers.

6. A projectile comprising a head and a body, interfitting parts on the head and body, a segmental core within the projectile and frictionally holding the head and body together, and a projection on the exterior of the body to facilitate stripping of the body upon penetration of an object.

7. A non-explosive projectile comprising a head and a body separably held together, and a core comprising a plurality of elements disposed within the head and body and removable therefrom upon separation of the head and body.

8. A projectile comprising a head and a body separably held together, a separable core disposed within the head and body and a projection on the exterior of the body to facilitate separation of the body upon penetration of an object.
